UNITED STATES PATENT OFFICE

1,991,608

METHOD OF BINDING BOOKS

Philip A. Frazier, Oak Park, Ill.

Application July 15, 1932, Serial No. 622,762

1 Claim. (Cl. 281—29)

This invention has to do with the binding of books and relates more particularly to an improved arrangement in the assembly of the parts of a machine-bound book.

5 In building a book, it is the present practice to attach a super, liner and sometimes a head band to the back of a group of signatures after they have been gathered, stitched and rounded, and before being "cased in". At the present time 10 covers are commonly called "cases".

In a hand-bound book, the case board is placed with an edge very close to the case joint, or, the groove is near the back of the book about which the sides of the case pivot relative the back. 15 Also, in a hand-bound book, the reinforcing material, i. e., the super and liner, and the end sheets are pasted while the case is open. This results in a freely opening book.

When books are cased by machine it has always 20 been necessary to close the case immediately after the gluing in of the backbone and pasting in of the end sheets. Because of the pervasion of the glue or paste and the hardening thereof with the book in the closed position the book often becomes difficult to open. To alleviate this 25 situation a greater space has been provided between the heretofore mentioned joint and the nearer edge of the case board. A surplus of case covering stock is thus left unsupported between the joint and the board. Those books are 30 then pressed between boards with beads thereon, it being the purpose of the beads to undulate this surplus stock inwardly. Nevertheless the case is relieved of its firmness by such unsupported 35 surplus stock. Even with a goodly space between the case joint and the case board it is often difficult to open the cover without lifting portions of the end sheets or tearing the sheets adjacent thereto because of excess glue having oozed 40 therebetween.

When the books are placed between boards with beads for pressing the surplus cover stock into a hinge-groove, they are placed on trucks 45 and transferred to a storage room for a period of twenty-four hours or so to permit the glue in the backbone of the books to have time to dry. Every book, when it is taken from the press, must be inspected to see that the end sheet, which is 50 used as the inside covering for the case, is free from glue or paste.

These operations are necessarily slow, expensive and time absorbing, so that among the objects of the present invention is the provision of: 55 An improved method of binding a book by ma-

chinery which builds into a book the free opening characteristics of a hand-bound book.

A method of binding a book which calls for the attaching of end sheets in the cover prior to the placing of that cover upon a group of signatures. 5

A cover for a book in which the end sheets are secured to the cover boards with a glue of the same pervasive and shrinking qualities as that for holding the cover to said boards and to 10 thereby preclude warping of the cover.

The improved process of binding a book which provides for the assembly of a super and other reinforcing material with the book cover before 15 its consolidation with a group of signatures.

An order in the events of building a book by machinery whereby the cover boards may be set in close proximity to the back of the book without likelihood of lifting the end sheets when the book 20 is opened for the first time.

The above objects and other desirable objects of the invention will be made apparent in the description hereinafter set forth with reference to the accompanying drawings hereby made a part of the specification and in which:

Figure 1 is a cross sectional view of a book embodying the present invention;

Figure 2 is a plan view of the inner side of the book cover illustrated upon the book in Figure 1;

Figure 3 is a view similar to that of Figure 1 30 but of a modification;

Figure 4 is a plan view of the inner side of the cover illustrated upon the book in Figure 2;

Figures 5 to 10, inclusive, are transverse sectional views of different forms of covers; 35

Figures 11 to 13, inclusive, are transverse sectional views of differently formed covers with end sheets attached;

Figures 14 to 17, inclusive, are transverse views of different forms of covers; and

Figures 18 and 19, inclusive, are transverse sectional views of modified forms of covers with end sheets attached.

Throughout the following description and in the drawings like reference characters indicate 45 similar parts.

For the improved method of book binding herein described, it is proposed to print the groups of signatures in a conventional way. These may be accumulated by a gathering machine in the 50 usual manner. They may be stitched by sewing machines as customary. In the new order of affairs, after sewing the book, it is trimmed rounded and backed, and is covered with a previously prepared case.

55

In the conventional method of preparing a group of sewed signatures, a four-page end sheet is stitched onto the first and last signature. The outer portion of such four-page sheet is the part which extends over the inner face of the cover boards at each side of the case. Paste is ordinarily used in the process of fastening the end sheets. In the present process, glue is to be substituted for paste.

10 In Figure 1 four-page end sheets 20 are shown as arranged within a bound book. These sheets are grouped and sewed commonly into position with the signatures 21 before the previously prepared case 22 is attached. Case 22 comprises a super 23, a liner 24, the case covering material 25 and cover boards 26 the latter being shown both in Figures 1 and 2.

15 The outer end sheets 20 may have upon their outermost faces mucilage or glue for causing the sheets to adhere to the respective inner faces of the cover boards and simultaneously to the margins 27 of the case covering material disposed upon the inner faces of the cover boards. The glue may be applied to the casing instead of to 20 the end sheet if desired.

20 Case 28 shown in Figures 3 and 4 is a slight modification of case 22. First, there is laid on the inner side of the center section of the cover material 29 a liner 30. Usually the liner 30 is 25 made of paper. The liner 30 is slightly narrower than the back of the book and shorter than the height of the book so that it does not show when the book is completed.

25 Glued to the inner face of the liner 30 is a super 31. The opposite edges of the member 31 are glued to opposed inner face margins of the cover boards 32 which may be glued to the inner face of the cover material 33 either before or after the application of the reinforcing members 30 and 31. Subsequent to the placing of the edges of the super 31 upon the cover boards 32 and to the placing of the margins 34 of the covering material upon the inner face of the cover boards 32, end sheets 35 are pasted to the inner faces of the 30 boards and over the exposed edges of the super and margins 34. The cover is thus completely prepared before attaching it to the assembled group of signatures 35a.

30 When the end sheets are in place, they are rolled so that they will be pressed flatly and neatly into shape. This rolling process also displaces any excess of glue which might have been placed between the adhering parts. Since the same type of glue is used upon both sides of the cover boards, 35 the strain thereon will be equally distributed and no warping will occur.

35 Rolling of the casing removes any excess of glue so that the boards quickly dry making it possible to immediately place the casing upon the group of signatures. However, this is not necessary and the casings may be prepared ahead of time when they are to be used and stacked in any convenient place.

40 End sheets 36 are attached to the opposite faces of the group of signatures by means of stitching or pasting to the first and last signatures. If the end sheets are stitched, it may be done simultaneously with the stitching of the signatures. 45 When the casing is to be attached to the back of the unbound signatures, a hot thin glue is applied either to the super 31 or to the backs of the signatures in a sufficient quantity that it will collect within the indentations between the 50 signatures to assist the stitching to hold the signatures in place as well as to hold the casing to the signatures.

55 Figures 5 to 19 illustrate different forms of cover construction which may be assembled with end sheets as the end sheets 20 shown in Figure 5 or as the end sheets 35 and 36 shown in Figure 10 3.

15 The type of construction shown in Figure 1 with reference to the end sheets is known as "case-in" while the type of construction shown in Figure 3 is termed "case-cover".

20 Several different forms of casing are exhibited in Figures 5 to 10, all of which are suitable for the four-page type of end sheet heretofore described in connection with Figure 1, and as is shown in dotted outline in Figure 5. The reference character 42 designates the end sheets in Figure 5. Throughout the Figures 5 to 10 the casing covering material and the cover boards will be designated by the reference characters 43 and 44, respectively.

25 A case for a tight bound book is shown in Figure 5 where a super 45 is attached to the back of the casing by means of glue over its entire outer face. The cover boards 44 are placed over both the opposite inner edges of the super member and over the inner disposed surfaces of the covering material 43 at the opposite sides of the super. A margin 46 of the covering material is turned over the edges of the cover boards at their exposed edges.

30 A different type of tight back casing is displayed in Figure 6 where a liner 47 is glued over its entire face to a center portion of the covering material 43. Similarly glued to the opposite and inner face of the liner 47 is a super 48. Placed upon the opposite inner edges of the member 48 and the opposed inner sections of the cover 43 are the cover boards 44. The unbound book and end sheets 42 shown in dotted outline in Figure 5 may be attached to the cover shown in Figure 6 in the same manner as shown in the first named figure. This operation may be performed either as soon as the cover is prepared or at some subsequent time.

35 Figure 7 illustrates a form of casing for a loose-bound book. Attached to the center section of the covering material 43 at opposite edges by means of strips of glue 49 is a liner 50. By attaching the liner 50 only at its edges, a space is left between said liner and the covering material 50 at the back of the book so that the liner and covering material may separate upon the opening of the book. Attached to the inner face of the liner 55 is a super 51 which projects beyond the edges of the liner and beneath the opposed edges of the cover boards 44. All contiguous surfaces shown in the figure are so held by means of glue.

40 The casing construction shown in Figure 8 varies from that of 5 only in the disposition of the super 52. Opposite longitudinal edges of the super 52 instead of being disposed between the covering material 43 and the cover board 44 are placed on the inner side of the cover boards along the back margin.

45 Figure 9 discloses a type of construction embodying a loose back. There is a liner 53 with its opposite longitudinal edges glued to the center section of the covering material 43 by strips of glue 54. Glued to the entire inner surface of the liner 53 is a super 55, with edges projecting beyond the edges of the liner to lie upon the inner face of the cover boards 44 and to be there glued.

50 The type of construction illustrated in Figure 10 differs from that of 9 in that the liner 56 instead of being attached to the covering ma-

terial 43 at its edges, is attached over its entire surface adjacent to the covering material. Super 57 is then laid over both the inner face of the liner 56 and inner adjacent margins upon the face of the cover boards 44.

A multiplicity of cover constructions is shown in Figures 11 to 13. In all of these, end sheets are attached independently of the unbound group of signatures. To the type of structure shown 10 in the group of Figures 11 to 13 the backs of a group of signatures 62 having end sheets 63 are glued, the structure of the unbound signatures with end sheets attached thereto being identical to that shown in Figure 3. The same reference 15 characters 58 and 59 are used in conjunction with this group of figures for designating the cover material and the cover boards.

In Figure 1, separate end sheets 64 are used for the opposite sides of the casing. Prior to the 20 placing of the end sheets 64 a super 65 is laid to the back center portion of the covering material 58 and with its opposed edges along its major dimension laid upon the adjacent edges of the cover boards 59. The entire face of the 25 super 65 adjacent to the covering material 58 is glued thereto making the cover of the type having a tight back.

A cover having a loose back is shown in Figure 12. By means of strips of glue 66 a liner 67 is attached to the inner side of the covering material 58. Commonly placed to the entire inner face of the liner 67 and to the adjacent margins along the inner face of the cover boards 59 is a super 68. Covering the glued edges of the super 35 68, the inturned inner edges of the covering material and the inner faces of the the cover boards are independent end sheets 70.

In Figure 13, there is shown a cover construction identical with the construction shown in 40 Figure 12 excepting that the liner 71 instead of being glued along opposed edges to the covering material 58, is glued over its entire face exposed to that material. A super 72 is glued to the inner face of the liner 71 and to the margins adjacent 45 and upon the inner faces of the cover boards 59. End sheets 73 are then glued into position as shown. Since the liner 71 is glued over its entire face to the covering material 58, the book is of the tight bound variety.

50 A group of differently constructed casings adapted to receive end sheets to be cased therein concurrently with the placing of a group of signatures is shown in Figures 14 to 17. The case covering material and cover boards are referred to by the numerals 79 and 80 consistently throughout the group. In Figure 14, a liner 81 is secured by means of glue to that part of the covering material which is to be disposed at the back of a completed book. Glued to the entire 55 inner face of the liner 81 is a second liner 82. There is glued to the inner face of the member 82 a super 83. Liners 81 and 82 and the super 83 may, if desired, be secured to one another before the liner 81 is attached to the covering material. Super 83 in addition to being glued to the liner 82, has its opposite and longitudinal edges glued to sections 84 of the covering material. The material 79 is articulated about the opposite edges of the super 83 to bring the inner 60 face thereof in a common plane to the inwardly exposed face of the super to facilitate the placing of the cover boards 80 commonly to a margin of the inner face of the super 83 and to the adjacent sections of the covering material. A narrow margin 85 about the edge of the covering ma-

terial is folded over the edges of the cover boards and suitably glued to the inner face of those boards as is common practice. The liners 81 and 82 and the super 83 are so conglutinated with the covering material as to form a tight bound book.

In Figure 15, there is glued a liner 86 with its entire adjacent face glued to the covering material 79. Opposite edges of a second liner 87 are glued to the inner face of the liner 86. Super 10 88 is then glued to the entire inner face of the liner 87. Disposed and glued to sections 89 of the covering material flanking the section of said material to which the liner 86 is attached are opposite edges of the super 88. As in Figure 14, 15 the covering material 79 is curled about the edges of the super 88 so that the cover boards may be placed evenly upon the edges of the super and to the outer sections upon the inner face of the sheet of covering material. Since there is a space between the liner members 86 and 87 which is not attached, the liner members may spread apart when the cover is placed upon a book and the book is opened.

A different form of casing having a loose back is 25 shown in Figure 16. In this figure there is a liner 90 attached to the center part of the covering material 79 by means of glue and having a second liner 91 secured to its opposite longitudinal edges by means of strips of glue 92. Over the whole of 30 the inner face of the liner 91 and to margins upon the inner face of the cover boards 80 is secured by means of glue a super 92.

Corresponding to liner 90 and 91 and the super 92 in Figure 16, there are in Figure 17 liners 93 35 and 94 and a super 95 to form a tight back cover. The difference in the two constructions as shown in Figures 16 and 17 is that the liner members in the first named figure are stuck together only at their edges while in the latter 40 named figure they are stuck together over their entire contiguous faces.

Figures 18 and 19 disclose case constructions suitable for the reception of a group of signatures having but a two-page end sheet attached 45 to either side thereof. A cover assembled with such a book is shown in Figure 3. In Figures 18 and 19, the covering material is designated by the numeral 96 while the cover boards are designated by the numeral 97.

Secured to the covering material 96 in Figure 18 at the central inner section thereof is a reinforcing strip 101 along its entire contiguous face. Fastened to opposite edges of the reinforcing strip, or liner, 101 by means of glued strips 102 55 is a second liner 103. To the inner face of the liner 103 is a super 104 suitably glued in place and with its longitudinal edges projecting over and onto the margins along the inner face of the cover boards 97. The liners 101 and 103 and the super 104 may be assembled with one another in the manner described before the liner 110 is attached to the covering material. End sheets 105 are then glued to the position shown in the figure. The unglued space between the two liners 60 makes this cover of the loose back type.

The type of cover shown in Figure 19 differs from the cover of Figure 18 in that there is no loose space between liners 106 and 107, the two members being glued tightly together. Liner 107 70 is glued to the center back portion of the covering material 96 while the inner face of the liner 106 has glued thereto a super 108. The edges of super 108 are held by means of glue between the end sheets 109 and the cover boards 97 in the 75

manner shown by means of glue. The end sheets are also glued in the position shown to the inner faces of the cover boards and over the inwardly disposed edges of the covering material.

5 In preparing a group of signatures for being encased in a previously prepared cover of the type of the present invention, it is desirable in certain instances to attach a thin paper reinforcing member directly to the backs of the signatures by a light coating of hot glue. Such a member assists in the binding of the signatures to one another. A side-sewed book may or may not have such a reinforcing member. A group of pages consolidated by the so-called patent binding is 10 always provided with such a reinforcing member.

15 A very marked advantage of the above recited and illustrated methods of preparing covers for a book is that the covers are assembled flat or in the position to be assumed when upon an opened book. Because of the natural flat structure of the casing and particularly of the natural position of the reinforcing material in the back thereof, the cover is easily opened after being placed upon a book. Heretofore only hand-bound books have been built with this desirable 20 characteristic.

25 Another advantage presents itself in corollary to the above advantage. Because of the freely opening qualities of the present type of cover, the end boards may be placed nearer to the cover back to result in a more rugged cover construction.

Since the glue which holds the reinforcing materials, i. e., the liner and super, upon the casing may become congealed before the cover is attached to the group of signatures, there is less soft glue at the back of the book when the signatures and end sheets are set and hence correspondingly less likelihood of glue spreading to surfaces between the end sheets, or between the end sheets and adjacent sheets. By this improved method of book binding, lifting or tearing of the end sheets or other sheets, when opening the book for the first time, has been materially reduced. It is the logical sequel that the undesired spreading of glue to exposed surfaces of the book is correspondingly reduced.

10 15 Having described the invention, what is claimed as new and desired to be secured by Letters Patent of the United States, is:

20 The method of binding a book that comprises the steps of gluing coverboards to opposite sections of a case covering material, gluing a super to the adjacent edges of said coverboards and to that section of said covering material intermediate said cover boards, affixing end sheets to the inner faces of said coverboards and over that 25 portion of the edges of said super that are glued to said coverboards, drying the glue while the case is in an open position, and then gluing to said super a group of signatures.

30 PHILIP A. FRAZIER
